(57) **CLAIM**

The ornamental design for a handbag with detachable head- phone handle, as shown and described.

DESCRIPTION

FIG. 1 is a front perspective view of a handbag with detachable headphone handle showing our new design;

FIG. 2 is a front elevation view thereof;

FIG. 3 is a rear elevation view thereof;

FIG. 4 is a left side elevation view thereof; the right side elevation view being a mirror image thereof;

FIG. 5 is a top plan view thereof; and,

FIG. 6 is a bottom plan view thereof.

The broken lines shown in the drawings illustrate portions of the handbag with detachable headphone handle that form no part of the claimed design.
